J. B. BRIDGES

RAIL ALIGNING TOOL

Filed April 30, 1927

Inventor

J. B. Bridges.

By Clarence O'Brien
Attorney

UNITED STATES PATENT OFFICE.

JAMES B. BRIDGES, OF RICHMOND, VIRGINIA.

RAIL-ALIGNING TOOL.

Application filed April 30, 1927. Serial No. 188,020.

This invention relates to new and useful improvements in tools for use in the aligning or proper gaging of trackway rails and aims to provide a highly novel, simple, and 5 easily operable device wherein rails may be drawn into proper gage and there maintained until they have been permanently spiked to the rail supporting ties.

Briefly the tool consists of a pair of 10 metallic straps equipped at their outer ends with means for engaging the rail bases, the inner ends of the straps being pivotally joined to a throw lever so associated with the strap that when swung into one direction the rail engaging ends of the straps will be brought inwardly for bringing the rails into proper gage.

Further, means is provided for association 20 with the clamping end of one of the straps for causing the further inward movement of that particular rail should its tread or the tread of the other rail be worn to any appreciable extent with the end in view that the treads of the rails are brought into 25 proper gage or alignment.

The invention further aims to provide a 30 lever attachment for the inner ends of the straps so associated with the straps as to facilitate the inward movement of the straps with respect to each other by the actuation 35 of the lever and this without requiring unusual strength on the part of the operator.

With the foregoing and other objects in 40 view as the nature of the invention will be better understood, the same comprises the novel form, combination and arrangement of parts hereinafter more fully described, shown in the accompanying drawing and claimed.

45 In the drawing wherein like reference characters indicate corresponding parts throughout the several views:

Figure 1 is a side elevation of my improved rail aligning tool as actually associated with a pair of rails and the same being drawn inwardly to proper gage by use of the tool and there maintained so that the rails may be permanently anchored to the ties.

50 Figure 2 is a top plan view thereof.

Figure 3 is a side elevation partially in cross section disclosing the tool per se as in extended position so as to facilitate the disposition of the rails within the opposite 55 ends of the strap.

Figure 4 is a detail perspective of the inner end of one of the strap members, and

Figure 5 is a perspective of one of the 60 filler plates for use in association with the rail engaging end of one of the straps so that that particular rail may be moved inwardly to a greater extent in the event its tread has become worn with the end in view that the treads of the rails will be disposed at the proper gage.

Now having particular reference to the drawing, my novel tool consists of a pair of 65 metallic straps 5 and 6, the outer end of each of which is twisted at right angles to the inner end so that said outer end will assume 70 a flat-like position for engagement beneath the base of the particular rail A. Furthermore the extreme end of each strap is turned over to provide a hook 7 for engagement 75 with the outer edge of the particular rail as clearly disclosed in Figures 1 and 2. Pivoted to each strap in spaced relation with the hooked end 7 thereof is a clamp plate 8, the outer end of which is bent slightly upwardly as at 9 for engagement over the 80 inner edge of the base of the particular rail A, the inner end of each plate being turned upwardly to provide an ear 10 so that the plate may be forcibly swung upon its pivot by hammer or other tool during the engagement or release of the plate from the rail. Furthermore, the inner end of each plate 8 is formed with an opening to register with the 85 opening in the metallic strap when the plate has been swung into rail engaging position in order that it may be locked to the metallic strap by reason of a pin 11 that is attached to its particular strap by a chain 12.

As more clearly disclosed in Figure 1, 90 the clamp plate 8 of the metallic strap 6 is spaced a greater distance from the hooked end 7 of the particular strap than is the plate 8 of the other strap 5. Should the tread of this strap engaging rail be worn at 95 its inner surface, a filler plate 13, see Figure 100 5, is arranged between outer edge of the rail and the hook 7 after which the clamping plate 8 is swung into engagement with the rail with the end in view that when the metallic straps are drawn together in a manner 105 hereinafter described, the tread of that particular rail will be moved in to a greater extent than the tread of the other rail so as to produce the proper gage or alignment. Should the tread be unworn, similar plates 13 110

are disposed at opposite edges of the rail base so that no further movement of that particular rail will be brought about than the movement of the other rail. As disclosed in Figure 5 this plate 13 is formed centrally with a notch 14 so that the ends thereof may engage at opposite ends of the hook 7 so as to prevent the movement of the filler plate. Furthermore, the width of these plates may be of predetermined area so as to compensate for the degree of wear of the rail treads.

The inner ends of the straps 5 and 6 are bent upwardly to provide ears 5' and 6', the upper ends of these ears being formed with circular openings so as to facilitate the pivotal attachment of the inner end of a throw lever 15 thereto. The inner face of the ear 6' of the strap 6 is formed with a circular boss 16 for engaging the inner edge of the ear 5' with the end in view of taking the strain off of the pivotal connections between the lever 15 and the ears 5' and 6'.

Obviously when the bases of the rails A—A have been rigidly secured within the ends of the straps 5 and 6, which straps are in outwardly extended position as indicated in Figure 3, a throwing of the lever 15 over into the position disclosed in Figures 1 and 2 will draw the straps inwardly into the position in said Figures 1 and 2 for securing the rails in proper gage so as to facilitate the rigid spiking of the same to the ties after which the tool may be removed.

It will thus be seen that I have provided a highly novel, simple and efficient rail aligning tool that is well adapted for all the purposes heretofore designated and even

though I have herein shown and described the invention as consisting of certain detail structural elements it is nevertheless to be understood that some changes may be made therein without affecting the spirit and scope of the appended claims.

Having thus described the invention, what I claim as new is:

1. In a rail aligning tool of the character described, a pair of metallic straps of predetermined length, turned over hooks upon the outer ends of the straps, pivotal clamping plates arranged upon each strap in inwardly spaced relation with respect to the hooks thereof, filler plates for disposition along one or both edges of one of the rails between the hook and clamp plate of one of the straps and means interconnecting the inner ends of the straps so as to facilitate the drawing of the same together.

2. In a rail aligning tool of the character described, a pair of metallic straps of predetermined length, means at the outer ends of the straps for engaging the treads of a pair of spaced rails, upwardly extending ears upon the inner ends of the straps, a throw lever pivoted at its lower end to the upper ends of the ears, and a circular boss upon the inner face of one of the ears surrounding its pivotal connection with the lever for engaging the adjacent edge of the other ear when the lever is thrown to draw the straps together at which point the ears will overlap so that the strain will be removed from the pivotal connections between the ears and the lever.

In testimony whereof I affix my signature.
JAMES B. BRIDGES.
